CLAIM

We claim the ornamental design for a BR40 LED lamp, as shown and described.

DESCRIPTION

FIG. 1 is a front elevation view of a BR40 LED lamp showing the new design;

FIG. 2 is a right side elevation view of the BR40 LED lamp thereof;

FIG. 3 is a left side elevation view of the BR40 LED lamp thereof;

FIG. 4 is a rear elevation view of the BR40 LED lamp thereof;

FIG. 5 is a top plan view of the BR40 LED lamp thereof;

FIG. 6 is a bottom view of the BR40 LED lamp thereof; and,

FIG. 7 is a perspective view of the BR40 LED lamp thereof. The broken lines in the figures represent unclaimed portions of the BR40 LED lamp and form no part of the claimed design.
